DESIGN FOR A HOLDER FOR MEMORANDUM PADS OR THE LIKE

Sabato Giliberti, Brooklyn, N. Y., assignor to Domenic Coppola, doing business as Gilbert Toy and Novelty Company, Brooklyn, N. Y.

Application October 16, 1942, Serial No. 108,541

Term of patent 3½ years

To all whom it may concern:

Be it known that I, Sabato Giliberti, a citizen of the United States and a resident of Brooklyn,
in the county of Kings and State of New York,
have invented a new, original, and ornamental Design for a Holder for Memorandum Pads or the like, of which the following is a specification, reference being had to the accompanying drawing constituting a part thereof, in which

Fig. 1 is a front elevational view of my holder showing my new design.

Fig. 2 is a side elevational view thereof.

I claim:

The ornamental design for a holder for memorandum pads or the like, as shown.

SABATO GILIBERTI.
